UNITED STATES PATENT OFFICE

JAMES ANDERSON, OF BIRMINGHAM, ENGLAND

ELECTRIC SWITCH OR CIRCUIT BREAKER

Application filed February 25, 1931, Serial No. 518,194, and in Great Britain February 27, 1930.

This invention relates to electric switches or circuit breakers, and particularly those required to control a large amount of power, the object of the invention being to provide 5 improved means for suppressing the arc which is produced between the switch contacts when the circuit is opened.

The invention comprises the combination of a fixed and a movable contact piece, a plurality of spaced plates arranged at right angles to the direction of movement of the movable contact, apertures in the plates through which the movable contact can pass, a magnet pole passing through the plates 10 and situated at one side of the said apertures in the plates, an iron or steel rod or rods arranged parallel with the magnet pole, and a magnet winding situated at one end of the said magnet pole and rods, the whole being 15 arranged and adapted to operate substantially as hereinafter described.

The accompanying drawing illustrates diagrammatically a switch constructed in accordance with this invention.

25 In carrying the invention into effect as shown, I arrange in combination with a fixed contact *a* a movable contact *b* consisting wholly or in part of a rod which is movable in an endwise direction to and from the fixed contact. The movable contact *b* passes through an aperture *c* in each of a group of brass or other nonmagnetic plates *d* arranged 30 parallel with each other, the plane of the plates being at right angles to the line of motion of the movable contact. The spacing of the plates is small so that the arc produced when the contacts are separated is divided into as many short portions as is convenient. Parallel with the movable contact 35 and also passing through the plates is an iron or steel rod *e* forming a magnetic pole by which a radial magnetic field is produced between each pair of plates. The pole carries an exciting winding *f* at one end, and the return path for the flux is provided by iron rods *g* between which the plates are mounted. To prevent or minimize the production 45 of eddy currents in the plates *d* when these 50 are made of metal, each plate may be formed

with a closed radial slit the edges of which are oxidized.

When the contacts are separated, the arc which is produced in a region surrounded by the plates, is moved laterally by the different 55 radial fields and is broken by the plates into small portions each of which passes into the air space between the adjacent pair of plates. There it is whirled through a curved path due to the radial disposition of the field and 60 is speedily extinguished.

By the means above described the suppression of the arc produced between the contacts when the circuit is opened is effected in a convenient and satisfactory manner. An 65 important advantage of the invention is that it enables a switch or circuit breaker adapted for a heavy duty to be constructed in a compact form.

The invention is not limited to the example 70 above described as subordinate details of construction or arrangement can be varied to suit different requirements.

In the example illustrated the contacts *a*, *b* 75 are auxiliary contacts, the main contacts being provided by a contact piece *h* at the lower end of the magnet core *e*. This contact co-operates with the movable main contact *i*. Both contacts *b*, *i* are mounted on a bar *j* carried by a movable stem *k* which can 80 be actuated in any convenient manner for moving the contacts *b*, *i*, into and out of engagement with the fixed contacts *a*, *h*. Also the contacts *b*, *i*, are resiliently mounted, being movable relatively to the bar *k* under 85 the control of springs *l*, *m*. The rods *g* and core *e* are associated with an iron plate *n*, and the rods *g* are insulated from the plates *d* by sleeves *o* and washers *p*. The magnet exciting coil *f* is connected at one end to the 90 terminal *q* and at the other end to the contact plate *a*. The switch illustrated is provided with two sets of the contacts above described. It is not essential to our invention 95 that the plates *d* shall be associated with auxiliary contacts, as they can be used with the main contacts when auxiliary contacts are not employed. On opening the switch, the main contacts *h*, *i*, separate before the auxiliary contacts; consequently the arc occurs 100

only between the auxiliary contacts *a*, *b*, and *c* is suppressed by the magnetic field associated with the plates *d*.

Having thus described my invention what I claim as new and desire to secure by Letters Patent is:—

1. In an electric switch or circuit breaker, the combination of a fixed and a movable contact piece, a plurality of spaced plates arranged at right angles to the direction of movement of the movable contact, apertures in the plates through which the movable contact can pass, a magnet pole passing through the plates and situated at one side of the said apertures in the plates, and a magnet winding situated at one end of the said magnet pole, the whole being arranged and adapted to break up the arc incident to the opening of a circuit and to simultaneously whirl the arc portions through circular paths between the plates, substantially as described.

2. In an electric switch or circuit breaker, the combination of a fixed and a movable contact piece, a plurality of spaced plates arranged at right angles to the direction of movement of the movable contact, apertures in the plates through which the movable contact can pass, a magnet pole passing through the plates and situated at one side of the said apertures in the plates, an iron or steel rod or rods arranged parallel with the magnet pole, and a magnet winding situated at one end of the said magnet pole and rods, the whole being arranged and adapted to break up the arc incident to the opening of a circuit and to simultaneously whirl the arc portions through circular paths between the plates, substantially as described.

3. In an electric switch or circuit breaker, the combination of a fixed contact piece, a sliding contact piece, a plurality of spaced plates arranged at one side of the fixed contact piece and at right angles to the direction of movement of the movable contact piece, apertures in the plates through which the movable contact can pass, a magnet pole passing through the plates and situated at one side of the said apertures in the plates, a magnet winding situated at one end of the said magnet pole at the opposite side of the fixed contact piece to the spaced plates, and iron or steel rods arranged parallel with the magnet pole at a greater distance from it than the holes in the spaced plates through which the movable contact piece slides, the whole being arranged and adapted to break up the arc incident to the opening of a circuit and to simultaneously whirl the arc portions through circular paths between the plates, substantially as described.

4. The combination with a switch or circuit breaker as claimed in claim 3, of main and auxiliary movable contacts, a member carrying said contacts, resilient means whereby the contacts can move relatively to the

carrying member, and a fixed contact on one end of the magnet pole with which the main movable contact co-operates, the other fixed contact associated with the spaced plates being the one with which the auxiliary movable contact co-operates, substantially as described.

In testimony whereof I have signed my name to this specification.

JAMES ANDERSON.
